UNITED STATES PATENT OFFICE.

HENRY B. MOGK, OF DETROIT, MICHIGAN.

CLOTHES WASHER.

Application filed June 9, 1927. Serial No. 197,592.

The present invention pertains to a novel clothes washer constructed particularly for domestic uses. The principal object of the invention is the provision of a simple device 5 of this character which operates on a suction principle and with great efficiency. The device comprises essentially a handle carrying an elastic suction cup. A passage is formed from the interior of the cup through the handle to the surface of the latter and is controlled by a check valve in the form of an elastic band surrounding the handle at an end of the passage.

The device is immersed in the liquid containing the material to be washed, and until reaching the material, functions substantially in the same manner as the washing bells now in use. On coming into contact with the clothes, the elastic suction cup is collapsed 20 by continued pressure on the handle, and the collapse results in a substantial decrease in the volume of the cup. Thus when the cup is raised the degree of rarefaction therein is considerably increased, and the pulling effect 25 on the clothes for removal of dirt therefrom is correspondingly increased. The elastic check valve opens on the compression stroke to permit exhaustion of the system and closes on the relief stroke to prevent entry of air 30 or water at the upper end thereof, so that the suction may act entirely on the clothes.

The invention is fully disclosed in the following description and in the accompanying drawing, in which—

35 Figure 1 is an elevation of the device; and Fig. 2 is a longitudinal section on the line 2—2 of Figure 1.

Reference to these views will now be made by use of like characters which are employed 40 to designate corresponding parts throughout.

The device includes a suction cup or bell 1 formed of an elastic material, preferably rubber, and having an exterior axial boss 2 formed therewith. The dome of the cup has 45 an aperture 3 establishing communication between the interior of the cup and the interior of the boss.

An elongated handle 4 is inserted in the boss 2 as a socket and is firmly held thereby 50 because of the elastic nature of the socket. If desired, other or additional securing means

between the boss and the handle may be provided. The lower portion of the handle has an axial passage 5 extending upwardly to a point slightly beyond the edge of the boss 2. 55 The lower end of the passage registers with the aperture 3, and the upper end communicates with a series of radial ports 6 drilled from the surface of the handle. Only one such port is actually necessary for communication between the interior of the suction cup and the atmosphere. A series of ports as illustrated enables a prompter and better distributed action. Finally, the outer ends of these ports are sealed by an elastic band 7 60 surrounding the handle.

In the operation of the device the suction cup is pressed upon a garment immersed in a shallow depth of water. The entry of the cup into the water compresses the air in the 70 cup and may cause the elastic band to stretch away from the ports 6 whereby such compressed air escapes to the atmosphere. When the cup is pressed upon the garment, it collapses and the air pressure in the system becomes sufficiently great to expand the seal 7 if it has not previously been stretched on immersion of the device. The elasticity of the cup and the collapse due to this property enables the formation of a rather high suction 75 in the system. The device is now raised on the garment so that the suction in the system may draw the dirt therefrom. After this operation is repeated several times, the garment is thoroughly washed.

Although a specific embodiment of the invention has been illustrated and described, it will be understood that various alterations in the details of construction may be made without departing from the scope of the invention 80 as indicated by the appended claims.

What I claim is:—

1. A clothes washer comprising a collapsible suction cup, a handle attached thereto, said handle having a passage communicating 95 with the interior of the cup, and leading to the surface of said handle, and a check valve applied to said surface and operable to permit free passage of air from said passage and prevent entrance of air thereinto.

2. A clothes washer comprising a collapsible rubber cup having an axial hollow boss

forming an axial socket at the top of the cup, a handle engaged in said socket, said handle having longitudinal and transverse passages communicating with the interior of the cup and open at the surface of the handle, and an elastic band sleeved upon said handle over the outer end of said transverse passages

and forming a valve permitting exit of air from said cup upon collapse thereof and preventing entrance of air into the cup through 10 said passages.

In testimony whereof I affix my signature.

HENRY B. MOGK.
